Specification for Design.

Patented Aug. 9, 1921.

Application filed March 5, 1921. Serial No. 450,104. Term of patent 14 years.

To all whom it may concern:

Be it known that I, JOHN W. PRICE, a citizen of the United States, residing at Baltimore, in the county of Baltimore and State of Maryland, have invented a new, original, and ornamental Design for a Tire-Tread, of which the following is a specification, reference being had to the accompanying drawing, forming part thereof.

The figure is a perspective view of a tire showing my new design.

I claim:

The ornamental design for a tire tread, as shown.

JOHN W. PRICE.
